UNITED STATES PATENT OFFICE.

CHARLES ALGERNON PARSONS, STANLEY SMITH COOK, AND LOUIS MORTIMER DOUGLAS, OF NEWCASTLE-UPON-TYNE, ENGLAND; SAID DOUGLAS AND COOK AS-SIGNORS TO SAID PARSONS.

LUBRICATING SYSTEM.

Application filed March 29, 1921. Serial No. 456,643.

To all whom it may concern:

Be it known that we, CHARLES ALGERNON PARSONS, STANLEY SMITH COOK, and LOUIS MORTIMER DOUGLAS, all subjects of the King of Great Britain and Ireland, and residing at Heaton Works, Newcastle-upon-Tyne, in the county of Northumberland, England, have invented certain new and useful Improvements in Lubricating Systems, of which the following is a specification for which we have filed applications in Great Britain under No. 30,370, December 4, 1919, and No. 3,372, January 27, 1921.

The present invention relates to systems such, for example, as those described in British patent application No. 18024 of 1919, in which a common pump is employed to pump oil through two or more paths. In such installations where oil coolers are arranged in parallel in different paths the coolers are so designed that in addition to reducing the temperature of the oil by the desired amount they oppose such relative resistance to the flow of the oil as to obtain the proper relation between the quantities of oil passing through the respective coolers, that is to say, with the required pressures at their outlets.

It has been found in practice, however, that through various causes these relative quantities are not as designed or required, and the resistances to flow through the coolers are liable to vary owing to variation in the quality and condition of the oil, or, most important of all, owing to choking.

The object of the present invention is to ensure that the relation between the quantities passing through the two coolers will be automatically maintained irrespective of the resistances of the coolers.

The invention consists in the employment in the oil circulating system of a piston valve which is responsive to the pressure of the oil in the discharge from each cooler and is so actuated that when the pressure in the discharge from one cooler falls below the pressure in the discharge from the other cooler, the supply in the latter cooler is restricted, while the supply to the former is increased.

The invention further consists in constructing the valve in such a manner that when the supply to one cooler has been restricted to a predetermined extent, any fur-

ther movement causing further restriction of this supply will cause the other cooler to be by-passed, so that in the event of complete or very considerable choking of either or both coolers, either or both of them will be automatically by-passed and a proper quantity of oil supplied to the system.

The invention further consists in the improved means for controlling the flow of oil in lubricating systems hereinafter described.

Referring to the accompanying drawings:—

Figure 1 is a plan view of one form of valve employed showing the oil outlets.

Figure 2 is a longitudinal section of the valve taken at right angles to Figure 1 and indicating diagrammatically the pipe connections to the coolers.

Figures 3, 4, and 5, illustrate modified forms of valve.

Figure 6 shows diagrammatically a complete lubricating system indicating the manner of connecting the valve.

In carrying the invention into effect according to the example shown in Figures 1 and 2, in which a common pump delivers oil to two different systems through two coolers 1 and 2 in parallel, there is provided a valve comprising two pistons 3 and 4 of the same diameter connected by a stem 5, which valve can slide freely in a cylindrical casing 6. Oil from the pump is admitted by an inlet 7 to the central portion of the casing between the pistons 3 and 4 and passed to the coolers through apertures 8 and 9 in the central portion of the casing. One aperture 8 or set of apertures is partially covered by the left hand piston 3 and leads to the cooler 1, while the other aperture 9 or set of apertures is partially covered by the right hand piston 4 and leads to the other cooler 2. The left hand end of the valve casing is connected by a pipe 10 to the oil outlet from cooler 1, so that the outer end of the piston 3 is subjected to the pressure in the system supplied through cooler 1, and, similarly, the right hand end of the valve casing is connected by a pipe 11 to the oil outlet from cooler 2.

The pressure of the oil between the pistons has no influence on the movement of the valve because the pistons are of the same area, but difference in the pressures acting on its outer ends, that is, difference

in the pressures at the cooler outlets, causes the valve to move towards the low pressure end. If the quantity of oil received by one system, say, that supplied through cooler 1, is defective, the pressure at the outlet of this cooler will fall and the higher pressure in the outlet from cooler 2 will move the valve to the left. The effect of this movement will be that the extent to 10 which the piston 3 covers the aperture 8 leading to cooler 1 will be reduced and the open area through the aperture thereby increased, while the extent to which the piston 4 covers the aperture 9 leading to cooler 15 2 will be increased, thereby reducing the open area. In consequence, the proportion of the total quantity passing through cooler 1 will be increased and the variation will proceed until the outlet pressures from the 20 two coolers are again equal. A defective supply through the cooler 2 would, of course, be rectified by the valve moving in the reverse direction.

The apertures 8 and 9 may be made of any 25 shape but are preferably of such form as to give a large movement to the valve and of such area that the pressure drop across them is small when the valve is in the normal position. As shown, the shape and size 30 of the apertures may be determined by diaphragms 12 and 13 of any desired form.

The pistons are provided with by-pass apertures 14 and 15 leading from the central space between the pistons through the cylindrical surfaces of the pistons. Each by-pass aperture is normally covered by the cylinder casing but is so disposed in relation to a recess 16 or 17 in the cylinder casing that when the inlet aperture to one 40 cooler has been restricted to a predetermined extent by one piston, the by-pass aperture in the other piston is over the recess which communicates with the outlet from the other cooler whereby the latter cooler is by-passed. 45 The movement of the valve in either direction is preferably limited by stops 18 so disposed that when the piston reaches them the by-pass aperture is sufficiently uncovered to pass the total quantity required for the system whose cooler has been choked.

If desired a light spring or springs may be provided to assist in bringing the valve to the normal position and to prevent jerkiness in action.

55 According to another modification illustrated in Figure 3, an additional by-pass is provided consisting of an aperture 19 in the cylindrical surface of the cylinder casing 6 near one end, say the left hand end, connected by a pipe 20 or the like to the other end of the casing, that is, to the outlet from the cooler 2. This aperture is normally covered by the left hand piston 3, but if the supply through cooler 2 is defective and the valve moves

to the right, when this movement has proceeded to a predetermined extent, the piston 3 will uncover the by-pass aperture 19 so that oil can pass through it and the pipe 20 from the outlet of cooler 1 to the outlet 70 of cooler 2. If this by-pass is not sufficiently effective to restore equilibrium the piston valve will move still farther to the right and open the previously described by-pass 15 from the inlet chamber of the valve to 75 the outlet from cooler 2.

It will be seen that the oil which passes through this additional by-pass 19, which is preferably arranged to operate before the by-pass 15, is oil which has passed through 80 a cooler, and this additional by-pass can be provided in connection with either or both coolers.

According to another modification, the aperture, through which oil passes to the 85 cooler inlets, may be provided in the inner ends of the pistons instead of in the cylinder casing. A valve constructed in this manner is illustrated in Figure 4 in which the pistons 3 and 4 are formed with slots 21 of 90 any suitable shape communicating with annular spaces 22 formed in the cylinder 6 and leading to the outlets 8 and 9 respectively. Instead of the by-pass apertures 14 and 15 grooves 23 are formed in the pistons 95 to establish communication between the annular spaces 22 and recesses 24. Oil can thus be by-passed from the central space of the cylinder 6 through the slots 21, annulus 22, groove 23, and recess 24 to either of the 100 pipes 10 or 11.

Figure 5 illustrates a form of valve applicable to the case in which the whole of the oil is passed through a primary cooler 1, that destined for the sprayers also circulating through a supplementary cooler 2. In this case the inlet 7 is connected to a point between the coolers and in the normal action of the valve only oil for the bearings 105 passes through the valve. Communication between the central space of the casing 6 and the outlet 8 is by means of apertures 25 in the cylinder within which the piston 3 fits. The normal pressure from the sprayer system acting on the outer side of the piston 4 suffices to keep it in the position shown.

If, however, this pressure drops owing to insufficient supply through the cooler 2, movement of the valve to the right takes place thereby causing a reduction of the open area through the apertures 25, and consequently an increased pressure in pipe 7 and an increased flow through cooler 2. When the valve has moved to the right by a predetermined amount a groove 26 is 120 uncovered and oil thereby admitted from the central space past the piston 4 directly to the sprayer system. Should the supply thus obtained not be sufficient a by-pass pipe 27 may be added by which oil passing 125

through the apertures 25 is also supplied to the sprayers through a groove 28, an aperture 29 and the piston 4. This valve may be usefully employed in the case in which 5 there is a gravity tank in the bearing circuit only. In that arrangement when the pumps are stopped, oil is supplied from the gravity tank through the pipe 8, apertures 25 and groove 26, or via the by-pass 10 27 to the sprayers.

Figure 6 illustrates the application of a valve of the type illustrated in Figure 2 to a complete lubrication system in which two distinct supplies of oil passed respectively through coolers 1 and 2 are delivered. The oil from both systems drains into a common tank 30 from which it is delivered to the distributing valve 6 by duplicate 15 pumps 31, 32 through filters 33. From the outlets 8 and 9 the oil is respectively led to the coolers to the systems to be supplied by pipes 36, 37. The outlet from the cooler 1 is also provided with a connection 38 to gravity tanks 39 from which by a pipe 40 20 the system connected to the cooler 1 may be fed. A by-pass 41 between the pipes 34 and 36 is also provided so that the cooler 1 may if required be cut out of action and oil supplied directly from the valve 6 either to 25 the gravity tanks 39 or to the lubrication system.

It will be seen that the invention is also applicable to installations in which the resistance to flow through one system is very 30 small in relation to that through the other system, as, for instance, when a cooler is provided in one of the paths only. In such cases the valve will automatically maintain such resistance to flow through the system without a cooler as to maintain equal oil pressures in the two systems supplied.

The control valve may be designed in several ways to give different discharge pressures. For instance, one of the piston 45 ends may be stepped and the annular spaces between the steps connected to atmosphere, or the difference in pressure may be obtained by causing a spring of sufficient strength to act on one end of the valve or the valve 50 may be placed vertically and made of sufficient weight to cause the difference in pressure required.

Having now described our invention, what we claim as new and desire to secure 55 by Letters Patent is:—

1. A lubrication system having two supply branches, a distributing valve in circuit therewith having a common inlet and a divided outlet, and reciprocable means within 60 the valve actuated by a differential pressure in the outlet branches whereby when the pressure in one branch falls below that in

the other the supply to the latter is restricted and that to the former is increased.

2. The system of claim 1 with two coolers 65 for the oil in circuit, said coolers having an inlet and an outlet, said valve being respectively connected to the outlets of said coolers whereby when the pressure in the discharge from one cooler falls below the pressure in the discharge from the other cooler, the supply in the latter cooler is restricted, while the supply to the former is increased.

3. In a lubrication system as set forth in 70 claim 1, in which the resistance to the flow of oil is normally greater through one path than through the other path, passing only the supply to the latter path through the distributing valve, the normal supply passing directly to the other path.

4. In a lubrication system as set forth in 75 claim 1, in which the resistance to the flow of oil is normally greater through one path than through the other path, passing only the supply to the latter path through the distributing valve, the normal supply passing directly to the other path, making the distributing valve responsive to the pressure at 80 a point in the path of greater resistance in such a manner that reduction in pressure at this point causes increase of pressure at the inlet to the path.

5. A distributing valve comprising in 85 combination a casing, two pistons connected together and fitting within said casing, an inlet and two outlets communicating with the space between the pistons, a by-pass in each piston and recesses in the casing adapted to co-operate with said by-passes.

6. A valve comprising a casing fitted with 90 two pistons connected by a common stem, an oil inlet communicating with the space between the pistons and two outlets also communicating with this space, each outlet adapted to be partially or completely closed 95 by one of the pistons, substantially as described.

7. In a lubricating system, in combination 100 a distributing valve having a casing, two pistons connected together fitted within said casing, an inlet in said casing communicating with the space between the pistons, and two outlets in said casing communicating with the same space, two coolers, pipes 105 fitted between the outlets of the distributing valve and the inlets of the coolers, and pipes leading from the outlets of the coolers to the space in the casing at the outer end of the pistons.

In testimony whereof we have signed our 110 names to this specification.

CHARLES ALGERNON PARSONS.

STANLEY SMITH COOK.

LOUIS MORTIMER DOUGLAS.
